UNITED STATES PATENT OFFICE.

WILLIAM G. LESCH, OF BUFFALO, NEW YORK.

WINDOW-SHADE BRACKET.

1,363,328.

Specification of Letters Patent. Patented Dec. 28, 1920.

Application filed December 8, 1919. Serial No. 343,230.

To all whom it may concern:

Be it known that I, WILLIAM G. LESCH, a citizen of the United States, residing at Buffalo, in the county of Erie and State 5 of New York, have invented certain new and useful Improvements in Window-Shade Brackets, of which the following is a specification.

This invention relates to that class of 10 window shade brackets which is formed with a screw and adapted to be screwed by hand into a window frame without the use of tools.

One object of the invention is to provide 15 a bracket which will take any width of shade when applied to any window frame. This is accomplished by constructing the bracket so it will fit on any part of the window frame and can be screwed into the corner of the molding as well as on the flat 20 surface.

Another object of the invention is to provide a bracket which will not mar the finish on the window frame.

25 Another object of the invention is to provide a bracket which is stronger and more rigid than the usual construction of wire brackets while at the same time of an improved design and simple and inexpensive to 30 manufacture.

This invention also consists in certain other features of construction and in the combination and arrangement of the several parts, as hereinafter described and pointed 35 out in the appended claims.

In describing my invention, reference will be had to the accompanying drawings, in which like characters denote like parts in the several views, and in which:

40 Figure 1 is a plan view of one bracket of the pair.

Fig. 2 is a side elevation of the same and showing it mounted in the corner of the molding of a window frame which is in sec- 45 tion.

Fig. 3 is the screw end elevation of the same bracket shown in Figs. 1 and 2.

Fig. 4 is a plan view of the second of a 50 pair of brackets, or the one which supports the spring end of a window shade.

Figs. 5 and 6 are, respectively, a side ele- 55 vation and an end elevation of the bracket shown in Fig. 4.

Each of the brackets is formed of a single 55 piece of wire or other suitable material, represented by 1 in the first bracket and by 14

in the second bracket. In Figs. 1, 2 and 3 the screw is 3 and formed on the end of the straight top portion 2 of the bracket, which is then looped to form a circular opening 4 60 to support the round journal of the shade roller, and continued in a horizontal line at 5. At 1 the bracket is curved downward and forming the brace 6 is bent upward to the part 7 which is curved upward and toward the screw point 3. At 8 the bracket is looped around the portion 2 near the inner end of the screw thread 3 and grips tightly into the groove 9.

Anchoring the brace 6 firmly at 8 in the 70 groove 9 makes it solid with the top portions 2 and 5, thereby making the whole bracket stronger than the usual construction in which the brace is loosely wound at one end around the top portion. This also is for the 75 purpose of holding 8 firmly and not allowing it to "give" when screwed up tightly against the surface 12 of the window frame 11 as in Fig. 2. 10 is a washer, preferably 80 of felt, mounted on the screw 3 and against the loop 8 to prevent the latter from mar- 85 ring the window frame surface 12.

13 is the molding sectional outline of a window frame and shows how my bracket 90 clears it when screwed into a corner, which 85 is not possible with the usual construction where the brace extends at a right angle to the screw portion and so requires a flat surface the full depth of the brace. Also in the latter construction the brace mars the 90 window frame the full depth of the brace when screwed in on account of "giving" where looped around the screw.

In Figs. 4, 5 and 6, 16 is the screw, 15 and 95 24 the straight top portions between which 17 is formed a downwardly projecting loop 18 to hold the flat spring end of the shade roller. 19 is the brace which is bent downward at 14 and diagonally up at 19 (see Fig. 6) to the portion 20 which curves upward 100 and toward the screw 16. 22 is a groove into which the end 21 is bent and firmly grips. 23 is the washer the same as 10 on bracket 1. These washers are preferably made with 105 a hole slightly smaller than the largest part of the threads on screws 3 and 16 to hold them in place while being handled.

The operation of my bracket will be readily apparent from the above description and the drawings.

I claim:

1. A window shade bracket made of wire

and having an end on which is formed a screw thread, and a groove near said thread, the opposite end of said wire forming a loop held in said groove, the remaining portion 5 of said wire shaped to form a support for a shade and a brace for said support and a washer on the tread side of said loop.

2. A window shade bracket made of wire and having an end on which is formed a 10 screw thread, and a reduced section of said wire near said thread, the opposite end of

said wire forming a loop held in said reduced section and the remaining portion of said wire shaped to form a support for a shade and a brace for said support. 15

In testimony whereof I affix my signature in the presence of two subscribing witnesses.

WILLIAM G. LESCH.

Witnesses:

GUSTAVE LESCH,

CHARLES B. MOULTHROP.
